(57) **CLAIM**

The ornamental design for a bicycle storage device, as shown and described.

DESCRIPTION

FIG. 1 is a perspective view of a bicycle storage device, showing its new design;

FIG. 2 is a front perspective view thereof;

FIG. 3 is a front view thereof;

FIG. 4 is a right-hand side view thereof;

FIG. 5 is a top view thereof;

FIG. 6 is a bottom view thereof;

FIG. 7 is a rear view thereof;

FIG. 8 is a left-hand side view thereof;

FIG. 9 is a sectional view taken along line 9-9 of FIG. 3;

FIG. 10 is a left-hand side view thereof showing a locking chain;

FIG. 11 is a front view thereof showing a locking chain; and, FIG. 12 is a perspective view thereof showing a locking chain.

The rear view and left-hand side view are omitted because these views are mirror images of the front view and the right-hand side view, respectively.

The broken lines shown illustrate portions of the bicycle storage device that form no part of the claimed design.
